Primary Examiner — Dana K Weiland

Assistant Examiner — Messina L Smith

(57) CLAIM

The ornamental design for a stuffed waffle maker, as shown and described.

DESCRIPTION

FIG. 1 is a front, right side perspective view of a stuffed waffle maker showing the new design;

FIG. 2 is a left side view of the stuffed waffle maker in FIG. 1;

FIG. 3 is a front view of the stuffed waffle maker in FIG. 1;

FIG. 4 is a right side view of the stuffed waffle maker in FIG. 1;

FIG. 5 is a rear view of the stuffed waffle maker in FIG. 1;

FIG. 6 is a top view of the stuffed waffle maker in FIG. 1;

FIG. 7 is a bottom view of the stuffed waffle maker in FIG. 1;

FIG. 8 is a front, right side perspective view of the stuffed waffle maker in FIG. 1 shown in an open configuration;

FIG. 9 is a front, right side perspective view of the stuffed waffle maker in FIG. 1 shown in an alternate configuration;

FIG. 10 is a front, right side perspective view of the stuffed waffle maker in FIG. 1 in a second alternate configuration;

and,

FIG. 11 is an, exploded perspective view of the stuffed waffle maker in FIG. 1 shown in an open configuration.

The broken lines in the drawings depict portions of the stuffed waffle maker that form no part of the claimed design.
